UNITED STATES PATENT OFFICE.

NICOLA TALARICO, OF TURNER, MAINE.

RAILWAY-TRACK-TAMPING MACHINE.

1,091,984.

Specification of Letters Patent. Patented Mar. 31, 1914.

Application filed July 22, 1913. Serial No. 780,552.

To all whom it may concern:

Be it known that I, NICOLA TALARICO, a citizen of the United States, residing at Turner, in the county of Androscoggin and State of Maine, have invented new and useful Improvements in Railway-Track-Tamping Machines, of which the following is a specification.

This invention is an improved railway track tamping machine for use in tamping between the ties of railroads and in making the roadbed, the object of the invention being to provide an improved machine of this character which is mounted on a car adapted to travel on the track and is provided with a suitable motor and with means for automatically tamping between the ties and making the roadbed, the invention consisting in the construction, combination and arrangement of devices hereinafter described and claimed.

In the accompanying drawings:—Figure 1 is a side elevation of a tamping machine constructed in accordance with my invention, showing the same arranged on a track and in operative condition. Fig. 2 is a vertical transverse sectional view of the same, on the plane indicated by the line *a—a* of Fig. 1. Fig. 3 is a vertical central sectional view of the same. Fig. 4 is a vertical transverse sectional view of the same on the plane indicated by the line *b—b* of Fig. 1.

For the purposes of my invention, I provide a suitable car or platform 9 which has wheels 2 for operation on the rails 3 of a railroad track. The car also carries a suitable motor which is here indicated as an electric motor 4 adapted to receive current from a trolley wire 5 and provided with a suitable conductor 6 for this purpose. The motor is here shown as mounted on a suitable stand 7 and is provided with a driving pulley 8. I also provide a frame 1 which is here shown as rectangular in form and is arranged transversely on and depends from the under side of the car or platform 1 and is fixed thereto. A vertical standard 10 which is rectangular in cross section is mounted for vertical movement in an opening in the upper side of the frame 9 at the center of said frame, and the said standard is provided at its upper end with a shaft 11 on which are an operating pulley 12 and an idler pulley 13. A power belt 14 is driven by the pulley 8 of the motor and may be engaged either with the pulley 12 or the pul-

ley 13 by a suitable shifter or belt shifter 15 which may be of the construction here shown or any other suitable construction.

A screw shaft 16, which is vertical, has its upper end secured to the lower end of the vertically movable standard 10 which carries the pulleys 12—13, the said screw being arranged in the center of the frame 9 and passing through and being vertically movable in unthreaded openings in a pair of spaced cross bars 17—18 with which the said frame 9 is provided. A traveling nut 19 is arranged between the said cross bars, engages the screw 16 and is formed with a crown gear 20, which is horizontally arranged and the teeth of which are engaged by a pinion 21 on the inner end of a shaft 22, the said shaft being mounted in bearings 23 with which the frame 9 is provided and being provided at its outer end with a hand crank 24 whereby it may be readily turned in order to cause the traveling nut 19 to be revolved and the said nut coacting with the screw 16 to raise or lower the standard 10, as may be desired.

Spaced from opposite sides of the frame 9 and equidistant therefrom are a pair of rock shafts 25 which are mounted in suitable bearings 26 with which the car or platform 1 is provided and each of these rock shafts has a series of cranks 27 and is also provided with a longer lever crank 28. Three of the cranks 27 are here shown on each shaft at points above and between the railway track rails and each shaft also has one of said cranks 27 near each end and at points on the outer sides of the track rails.

Each rock shaft operates a gang of shovels or tamps 29 each of which has an operating rod 30, the said rods having their upper ends connected to bearing yokes 31 and the said bearing yokes being mounted on the wrists of the cranks 27. The rods 30 of the tamps or shovels pass through and are movable in openings 32 in suitable guide frames or supports 33, each of which is provided at suitable points with a pair of supporting rack arms 34. The said guide frames 33 are arranged at opposite sides of the frame 9 and their respective rack arms 34 engage the upper and lower sides of openings 35 on a shaft 36 which is mounted in bearings in the frame 9 and the front end of which is provided with a hand crank 37 whereby it may be revolved. The said rack arms 34 also pass through suitable

guides 38 with which the frame 9 is provided. An operating yoke 39 is mounted for vertical reciprocating movement above the car or platform 1, is guided by a suitable frame or other guide 40 and has depending arms 41, each of which has a slot 42 at its lower end. The wrists of the lever cranks 28 have their bearings and are movable in the said slots 42, the lever cranks of the rock shafts 25 being thereby connected to the said operating yoke.

The pulley 12 has a crank pin 43 to which is pivotally connected the upper end of a pitman 44, the lower end of the latter being pivotally connected to the center of the operating yoke. It will be understood that when the pulley 12 is driven by the motor 4, its crank pin and the pitman 44 impart vertical reciprocating motion to the yoke 39, that said yoke through the instrumentality of the lever cranks 28 causes the crank shafts 25 to rock and, hence, the cranks 27 of said shafts alternately raise the tamps or shovels and drive said tamps or shovels downwardly, thus causing the tamps or shovels to operate on the roadbed, between the ties.

The gangs of tamps or shovels may be adjusted toward each other according to the width of the ties and for operation on the roadbed in the space between the ties by properly turning the shaft 36 so as to cause its openings 35 by coaction with the rock arms 34 to move the guiding frames 33 of the tamps or shovels toward and from each other, as will be understood.

By lowering the frame, the standard 10 which carries the operating pulley 12, the said pulley and, hence, also the operating yoke 39 will be lowered, thus causing the said yoke to turn the lever cranks 28 of the rock shafts 25 downwardly and raise the cranks 29 of said rock shafts and hence, cause the tamps or shovels to be drawn upwardly by said cranks 28 to a sufficient height above the railway track and thus permit the car to be moved from point to point. The depth at which the shovels or tamps operate may be controlled by thus raising or lowering the standard 10 by means of the travelling nut 19, the screws 16 and the coacting devices hereinbefore described.

I have herein shown an electric motor for operating my improved tamping machine but I would have it understood that the motor may be of any type as, for instance, it may be a steam engine or an internal combustion motor as may be desired when the tamp is for use on steam or other railways not provided with electric current.

While I have herein shown and described a preferred form of the invention, I would have it understood that changes may be made in the form, proportion and construction of the several parts without departing from the spirit of the invention and within the scope of the claims.

I claim:

1. In a machine of the class described, the combination of a supporting frame, a pair of rock shafts mounted therein and each having cranks and also provided with a crank lever, tamps or shovels connected to the cranks of the rock shafts for operation thereby, guides for said tamps or shovels, a revoluble driving element, a vertically movable operating element actuated by the revoluble driving element and connected to the wrists of the lever crank of the rock shafts to impart rocking motion to said rock shaft, and having slots in which the wrists of the lever crank operate.

2. In a machine of the class described, the combination of a supporting frame, a rock shaft mounted therein and having cranks and, also provided with a crank lever, tamps or shovels connected to the cranks of the rock shaft for operation thereby, a guide for said tamps or shovels, a revoluble driving element, and an operating element actuated thereby and connected to the wrist of the lever crank of the rock shaft to impart rocking motion to said rock element, and means to raise and lower said driving element for the purpose set forth.

3. In a machine of the class described, the combination of a supporting frame, a standard mounted for vertical movement therein and having an elevating screw, a swivelly mounted adjusting nut engaging said elevating screw, means to operate said nut and cause the latter through the instrumentality of the screw to raise or lower said standard, a rotary driving element carried by said standard, a rock shaft having cranks and also provided with a crank lever, tamps or shovels connected to the cranks of the rock shaft for operation thereby, a guide for said tamps or shovels, and an operating element actuated by the revoluble driving element and connected to the wrist of said crank lever, for the purpose set forth.

In testimony whereof I affix my signature in presence of two witnesses.

NICOLA TALARICO.
